UNITED STATES PATENT OFFICE.

MORRIS R. HOROVITZ, OF BROOKLYN, NEW YORK, ASSIGNOR TO STANDARD METAL SPINNING CO., OF NEW YORK, N. Y.

DESIGN FOR STAMPING FOR LIGHTING FIXTURES.

Application filed June 17, 1922. Serial No. 2,713. Term of patent 7 years.

To all whom it may concern:

Be it known that I, MORRIS R. HOROVITZ, a citizen of the United States, and residing at Brooklyn, in the county of Kings and State of New York, have invented a new, original, and ornamental Design for Stamping for Lighting Fixtures, of which the following is a specification, reference being had to the accompanying drawing, forming part thereof.

Fig. 1 is a side view of a stamping for lighting fixtures, showing my new design.

Fig. 2 is a bottom plan view of the same. I have shown the design applied to a husk for lighting fixtures although it will be apparent that the design can be used on any stamping for lighting fixtures.

I claim—

The ornamental design for a stamping for lighting fixtures, as shown.

MORRIS R. HOROVITZ.
